Attorney

UNITED STATES PATENT OFFICE.

JAMES M. EIFFE, OF FULTONVILLE, NEW YORK, ASSIGNOR TO WHITE MOP WRINGER COMPANY, OF FULTONVILLE, NEW YORK, A CORPORATION OF NEW YORK.

MOP PAIL.

Application filed May 24, 1923. Serial No. 641,117.

To all whom it may concern:

Be it known that I, JAMES M. EIFFE, citizen of the United States, residing at Fultonville, county of Montgomery, State of New York, have invented a certain new and useful Improvement in Mop Pails, and declare the following to be a full, clear, and exact description of the same, such as will enable others skilled in the art to which it pertains to make and use the same, reference being had to the accompanying drawings, which form a part of this specification.

My invention relates to an improvement in mop pails shown in the accompanying drawings and more particularly described in the following specification and claims.

It is well known that the type of mop wringer adapted to straddle the rim of an ordinary pail is apt to cause the pail to be easily overturned thereby spilling the water contained therein upon the floor. It has also been found that in actuating the lever of the wringer to express water from the mop that the ordinary pail is apt to upset thus resulting in spilling the water.

A further objection to the common metallic pail when used to support a mop wringer is that the pressure exerted upon the pail is apt to cut or bend its rim. A still further objection to the ordinary pail is that the bottom of the pail is not sufficiently rigid to withstand the strain due to the operation of the mop wringer.

A further objection is that in the use of the ordinary cylindrical pail there is not sufficient room in front of the wringer to insert the mop into the pail and upon expressing the water from the mop the water is apt to be projected over the opposite edge of the pail.

The primary object therefore of the present invention is to overcome these and other objections to the ordinary pail when used to support a mop wringer and one of the features of the present invention consists in constructing the pail in an elliptical form in horizontal cross section in order that the mop wringer may be suspended on one of the narrow ends of the long diameter of the ellipse that there may be ample room to permit the mop to enter the pail in front

of the wringer before inserting the mop in the wringer to express the surplus water contained therein.

A further object of the invention is to provide a rigid rim for supporting the wringer,—said rim being reinforced by a pair of semi-circular straps, spot-welded thereto, having outstanding ears punched to receive a bail.

A further object of the invention is to provide reinforced intersecting strap members spot-welded to the bottom of the pail having projecting lugs or domes,—formed on the return-bends at the ends of the straps which serve as skid contact points, whereby the pail when filled with water may be readily pushed along the floor without lifting.

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

In the drawings accompanying this specification:

Figure 1 is a perspective view of a pail embodying my invention showing in dotted lines a mop wringer supported upon its rim.

Figure 2 is a vertical cross sectional view of a detail showing the wall and a portion of the bottom of the pail to which is spot-welded one of the reinforcing strips with its projecting lug or skid-dome,—also the reinforcing band at the top of the pail below the rim.

Figure 3 is an inverted plan view showing the intersecting reinforcing straps and their raised dome-lugs or skid points.

Figure 4 is a plan view of the pail showing the projecting ends of the reinforcing band at the top of the pail to which the bail is pivoted.

Referring now to the letters of reference placed upon the drawings:

A denotes a pail formed of sheet metal of elliptical shape in horizontal cross section.

B indicates the annular wall of the pail having a return-bend at its longer edge to receive the flange C¹ of the bottom plate C.

- 5 D, D, denotes reinforcing strips preferably spot-welded to the bottom of the pail with return-bends D¹, spaced from the body portion and provided with a projecting dome or cup-shaped lug D² forming skid points by which the pail may be pushed over the floor without lifting it therefrom. To provide a smooth finished edge the straps are bent back upon themselves as indicated at D³.

15 The upper edge of the pail is bent to enclose an encircling wire rim E,—and beneath the rim the wall of the pail is preferably vertical for a suitable distance sufficient to receive a pair of arc-shaped reinforcing straps F, F, which may be spot-welded to the wall of the pail;—the adjacent ends of which are bent outwardly on opposite sides of the pail to form ears which are pierced to receive the ends of a bail G, looped there-
25 through.

H denotes a mop wringer indicated in dotted lines suspended on the rim of the pail.

It will be apparent that the elliptical form of the pail,—in horizontal cross section,—provides ample room for the mop to be immersed in the pail in front of the wringer before inserting it in the latter to express the surplus water.

35 It will also be noted that the pail is not apt to be tipped either through the operation of the wringer or as a result of the overhanging weight of the latter,—as frequently occurs when the ordinary circular pail in cross section is employed.

40 It will be apparent that the reinforced upper edge of the pail provides a strong and rigid construction which is not apt to be injured through the operation of the wringer,—while the reinforcing cross members at the bottom of the pail serve to stiffen the structure against strain due to the operation of the device, so also the skid cups or domes provide convenient means for slid-

ing the pail over the floor without the necessity of lifting it therefrom. 50

Having thus described my invention what I claim is:

1. A mop pail formed of sheet metal, a pair of intersecting straps attached to the bottom of the pail having return-bends at their respective ends spaced from the body portion of the straps, said ends having cup-shaped projections adapted to support the pail in spaced relation to a floor, whereby the pail may be readily pushed over a floor or other supporting surface. 55

2. In a device of the character described, a pail formed of sheet metal elliptical in horizontal cross section, a pair of intersecting reinforcing straps formed of sheet metal secured to the bottom of the pail having their ends bent backwardly adjacent the end walls of the pail in spaced relation to the body of the straps, the spaced ends of said straps having semi-circular projections adapted to support the bottom of the pail in spaced relation to the floor on which it may rest. 65

3. In a device of the character described, a pail formed of sheet metal, its annular wall being elliptical in horizontal cross section, reinforcing straps spot-welded to the bottom of the pail with their ends bent backwardly in spaced relation to the body of the straps, the ends of said straps having semi-circular projections adapted to support the bottom of the pail in spaced relation to the floor on which it may rest, an annular elliptical wire ring enclosed within the upper edge of the pail wall, a pair of arc-shaped reinforcing straps located below the wire rim secured to the wall of the pail, said straps having outwardly projecting ears, pierced to receive the ends of a bail, 70 and a bail having its ends looped through the respective ears. 80

In testimony whereof, I sign this specification in the presence of two witnesses.

JAMES M. EIFFE.
